GOLF CLUB HEAD

William H. Jacobs, Akron, Ohio

Application September 7, 1949, Serial No. 4,883

Term of patent 14 years

(Cl. D34—5)

To all whom it may concern:

Be it known that I, William H. Jacobs, a citizen of the United States, residing at Akron, in the county of Summit and State of Ohio, have invented a new, original, and ornamental Design for a Golf Club Head, of which the following is a specification, reference being had to the accompanying drawing, forming a part thereof;

In the drawing:

Fig. 1 is a front elevational view of a golf club head, showing my new design;

Fig. 2 is an end elevational view taken from the left of Fig. 1;

Fig. 3 is an elevational view showing the side opposite that shown in Fig. 1;

Fig. 4 is a sectional view taken on the line 4—4 of Fig. 3; and

Fig. 5 is a sectional view taken on the line 5—5 of Fig. 3.

I claim:

The ornamental design for a golf club head, substantially as shown.

WILLIAM H. JACOBS.
